DESIGN FOR A TOY SIGN

Charles W. Jackson, Rocky River, Ohio

Application October 13, 1937, Serial No. 72,141

Term of patent 7 years

To all whom it may concern:

Be it known that I, Charles W. Jackson, a citizen of the United States, residing at 43 Buckingham Road, in the city of Rocky River, county of Cuyahoga, and State of Ohio, have invented a new, original, and ornamental Design for a Toy Sign, of which the following is a specification:

My design is represented in the accompanying drawing which constitutes a part hereof, and to which reference is made, and in which:

Fig. 1 is a front elevational view of a toy sign, showing my new design; and

Fig. 2 is a top plan view thereof.

I claim:

The ornamental design for a toy sign as shown.

CHARLES W. JACKSON.
